UNITED STATES PATENT OFFICE

NORA HOFFMAN, OF NEW YORK, N. Y.

DRESS FORM

Application filed January 20, 1928, Serial No. 248,201. Renewed June 17, 1931.

This invention relates to improvements in dress forms and has particular reference to an adjustable dress form.

The primary object of the invention resides 5 in a dress form which may be adjusted to the size and shape of a particular person to assure an accurate measurement and fit by dressmakers in the making of a lady's garment.

10 Another object of the invention is to provide an adjustable dress form which includes an inflatable form body for receiving an adjustable form jacket, which jacket is first applied to a person for whom a dress is to be made and adjusted to conform to the size and shape of the person, after which it is removed and applied to the inflatable body and the same inflated to fill out the same, which results in a dress form of a shape 15 and size corresponding to the person and to which the dress to be made is fitted during the making thereof.

A further object is the provision of a dress form which embodies a form jacket having 20 pleats suitably arranged therein for the purpose of allowing a limited adjustment to fit figures of different sizes and shapes, and which pleats may be taken in and held by suitable lacing for maintaining the garment 25 in an adjusted position after its removal from a person whose body measurements are required for dressmaking purposes.

A still further object is the provision of an adjustable dress form which is easy to 30 adjust and move from place to place, and which can be taken apart and stored away in a minimum amount of space.

With these and other objects in view, the invention resides in certain novel construction 35 and combination and arrangement of parts, the essential features of which are hereinafter fully described, are particularly pointed out in the appended claims, and are illustrated in the accompanying drawings, in 40 which:—

Figure 1 is a perspective view looking toward the front of my improved dress form with the adjustable jacket thereon.

Figure 2 is a similar view but looking toward the rear.

Figure 3 is a detail perspective view of the inflatable form body.

Figure 4 is a plan view of the adjustable form jacket in a flat condition.

Figure 5 is a detail horizontal sectional view through one of the box pleats. 55

Figure 6 is a vertical longitudinal sectional view on the line 6—6 of Figure 1.

Figure 7 is a detail vertical sectional view 60 on the line 7—7 of Figure 6.

Figure 8 is a detail horizontal sectional view showing the manner of fastening the form body to its supporting platform.

Referring to the drawings, the reference numeral 10 designates my improved dress 65 form in its entirety which includes an inflatable form body 11 supported upon a stand 12. The form body 11 is constructed of an inner rubber bladder 13 and is of the general shape of a woman's bust or torso. The same 70 is capable of being distended to various positions which is limited by an outer covering of inelastic material 14 to be hereinafter fully explained.

The inflatable body 11 has an air pressure 75 valve 15 suitably arranged in the wall thereof and permits of the inflation of the form by the use of a bicycle pump or the like, and which normally prevents the escape of air from the body but which may be manually 80 actuated to release the same for deflation purposes. The inner bladder 13 has a central longitudinal tubular portion 16, the walls of which converge upwardly as shown in Figure 6 of the drawings. The outer covering 85 14 is also provided with a tubular portion 16' corresponding to the general shape of the tubular portion 16 and extends therethrough. The bottom edges of the outer fabric covering are free and are provided with male fastening elements 17 for co-action with female elements on the stand 12 which will be hereinafter fully described.

The stand 12 comprises a base 18 from which a tubular rod or standard 19 rises. The tubular rod may be threaded into the base to facilitate its removal therefrom for packing and storage purposes. Slidably mounted in the tubular rod is a second tubular rod 20 of a smaller diameter and which is held in vari- 95 100

ous positions of vertical adjustment by a set screw 21. A platform 22 is threaded to the top of the rod 20 while a third rod 23 threads into the upper end of the rod 20 and rises upwardly from the base. The top end of the rod 23 has a head 24 thereon by which the form may be grasped and carried from place to place. The rod 23 extends through the central tubular portion of the form and tends to prevent lateral or swinging movement of the same. The side peripheral edge of the platform and top face thereof is provided with female elements 25 to receive the male elements 17 whereby the form is removably held upon the platform. The male and female elements shown in the drawings represent snap fasteners but any other suitable fastening means may be provided if desired, such as hooks and eyes or the like. When assembling the form upon the platform for use, the fastening elements are connected before inflation of the body and the rod 23 inserted through the tubular passage and screwed into the top end of the rod 20.

25 The bust portion of the bladder is open from front to back to provide a passage for flexible tie cords 26 which tend to shape and secure the outer covering 14 to the inflatable bladder. The tie cords also hold the tubular portion 16' snug against the rod 23.

30 In practice, the inflatable bladder is constructed to enable inflation of the same to any size, while several outer coverings may be provided for use in connection therewith, each 35 of which is capable of use for a predetermined number of different sizes, such as for instance, when the form is for use as a 32 to 36, an outer covering which will allow inflation of the form to these sizes and any intermediate 40 sizes will be applied. Briefly, the outer covering limits inflation of the form body to a predetermined size. However, the correct size desired is obtained by the attachment of a form jacket 27 which will now be described.

35 The form jacket 27 comprises an adjustable garment having a front piece 28 provided with an inverted box pleat 29 extending the length thereof, side pieces 30 having similar inverted box pleats 31 extending the length thereof, and back pieces 32 and 33 having hooks and eyes 34 and 35 respectively provided on their longitudinal free edges. The back piece 33 has an inverted box pleat 36 extending the length thereof. The free edges of all the inverted box pleats are provided with eyelets 37 for receiving laces 38 by which the pleats may be taken in or let out when fitting the jacket to a wearer. The 40 side pieces 30 are provided with arm holes 39 while the top edge of the jacket is shaped to fit over the shoulders of a person and may be adjusted thereto by providing eyelets 40 along the top edge to receive shoulder lacing 41.

In actual practice the jacket 27 is applied to the person for whom a dress is to be made, whereupon the same is buttoned up the back by fastening the co-acting hooks and eyes 34 and 35. The lacings are then pulled tight 70 which shapes the jacket to the body form of the person. By reason of the location of the adjustable pleats, the jacket may be accurately and snugly fitted to the person, whereupon it is removed by unfastening the hooks and 75 eyes 34 and 35, without disturbing the lacings. The jacket is next applied to the inflatable form, and the form inflated until the jacket is fully expanded.

80 A replica of the form of the person is therefore provided and may be used for obtaining the desired measurements in the making of a garment and for fitting the garment thereto during the making of the same. It will be understood that the jackets may be made to 85 fit forms of a limited amount of sizes, but it is believed that two jackets will be capable of adjustment to all size persons. One jacket may be made for adjustment from a small size to an average size, while a second jacket 90 may be made to fit persons from an average size to an extremely large size. The adjustments of the jackets compensate for any intervening sizes.

95 From the foregoing description, it will be seen that I have provided an adjustable dress form which may be accurately adjusted to the form of the person for whom a dress is to be made and which may be taken apart when not in use for packing and storing purposes.

100 While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

110 What is claimed as new is:—

115 1. A dress form comprising in combination with a platform, a fabric member having an outer tubular wall and an inner tubular wall, 115 said fabric joined at the top between said walls, the inner walls thereby providing a tube open at the top, the bottom edge of said inner wall turned outwardly and removably attached to the top of said platform, the bottom edge of said outer wall turned inwardly and removably attached to the periphery of said platform, a rod rising from said platform and disposed within the tube of the inner wall to support the latter, and a continuous 120 inflatable member having also outer and inner tubular walls and disposed within said first tubular walls, said latter member having a valve therein, the latter projecting through said fabric member, whereby said inner mem- 125 ber

130

ber is inflatable, substantially as and for the purpose described.

2. The method of reproducing the shape of the human body in a dress form which comprises the application of a jacket to the body of the subject, then connecting the jacket along the open edge, then lacing in the jacket to the contour of the body of the subject, then separating the jacket at the open edge and removing it from the subject, then connecting the open edge, and finally inserting an inflatable element in the jacket and inflating it to extend the jacket to assume the contour given it by the adjustment of the lacing while on the body of the subject.
3. The method of reproducing the shape of the human body in a dress form which comprises the application of a jacket to the body of the subject, then taking up the jacket at different points to adjust it to the contour of the body of the subject, then removing it from the subject without disturbance to said adjustments, and finally placing it on an inflatable form and inflating the latter to effect extension of the jacket to assume the contour given to it by the takeup adjustments made while on the body of the subject.

In testimony whereof I have affixed my signature.

NORA HOFFMAN.
